OF NEW YORK.

CHECKWRITER.

1,307,567.

Specification of Letters Patent. Patented June 24, 1919.

Application filed November 15, 1915. Serial No. 61,537.

To all whom it may concern:

Be it known that I, CHARLES G. TIEFEL, of Rochester, in the county of Monroe and State of New York, have invented certain new and useful Improvements in Check-writers; and I do hereby declare the following to be a full, clear, and exact description of the same, such as will enable any person skilled in the art to which the invention appertains to make and use the same.

The present invention relates to printing machines of the hand operated variety used for marking checks with a protective inscription, and, more particularly, to the machines of this variety known as "check writers," in which the printing characters include words of varying length, and a mechanism is provided for feeding the paper corresponding variable distances between the printing impressions.

The main object of the invention is to provide a machine of this type having a simple and efficient feeding mechanism operating to advance the work by the application of a positive force, and to accurately determine and precisely control the extent of the feeding movement.

Other objects and advantages will appear in connection with the following more detailed description of one embodiment of the invention illustrated in the accompanying drawings, in which:—

Fig. 1 is a top plan view of the machine.

Fig. 2 is a side elevation thereof.

Fig. 3 is a top plan view of the machine with the cover of the casing removed to expose the interior parts.

Fig. 4 is a side elevation in section for showing the interior parts.

Fig. 5 is a detail of a portion of the feeding mechanism looking toward the front of the machine.

Fig. 6 is a similar view, looking toward the rear of the machine, showing two positions of the actuating pawl.

Fig. 7 is a view similar to Fig. 6, showing the member for tripping the pawl in a different position.

The printing machine embodying the present invention comprises a frame having a base portion 10, and an upper portion, or housing, 11, which portions are rigidly connected so as to leave therebetween a work receiving slot 12 above a supporting bed 13 on the lower portion of the casing.

The housing 11 has journaled therein a shaft 14 on which is fixed a type carrier, or cylinder, 15, on the periphery of which are fixed a plurality of types 16 extending axially of the cylinder in spaced relation. For 60 rotating the carrier there is fixed on the shaft 14 a gear 17 (Fig. 3), with which meshes a gear 18 fixed on a shaft 19 journaled in the wall of the housing and carrying exteriorly thereof a knob 20. The gear 65 18 is larger than the gear 17 so that by turning the knob 20 through a portion of a revolution the type cylinder may be conveniently moved through a complete rotation to bring any one of the types to the common printing position at the bottom of the cylinder adjacent the work supporting bed 13.

For indicating the position of adjustment of the carrier in the selection of the type, there is provided, preferably, a drum 21 75 (Fig. 3) fixed upon the shaft 14, about which drum is wrapped a belt 22 (Fig. 4) which extends upwardly in crossed relation, and passing over supporting pulleys fixed on the casing, carries a pointer 23 extending over 80 a dial 24 attached to the cover of the casing so as to be readily visible from above the machine. This dial is provided with characters corresponding to the types on the carrier, and so arranged that when the pointer 85 is brought into register with any character on the dial by turning the knob 20, the corresponding type is thus brought individually and selectively to the common printing position.

The types may be inked by any suitable contrivance, and there is shown for this purpose in the present instance an inking roll 25 rotatably carried on an arm 26 of a lever pivoted on a spindle 27 supported in the 95 housing, and the roll is held in rolling contact with the type on the cylinder by means of a spring 28 fixed to the other end of the lever.

Journaled in the upper portion of the 100 housing is a shaft 29 which extends without the housing at one end, and has attached thereto the main operating member, or crank, 30. Fixed on the shaft 29 is a cam 31 adapted during the latter part of each revolution of the shaft 29 to engage and rock the arm 32 of a bell crank lever fixed on a shaft 33 which is journaled at its ends in the housing. This lever has a forwardly extending arm 34 carrying in a socket at its end a 110

platen member 35 adapted to be raised by the rocking of the lever through an opening 36 in the bed 13 into contact with the type which is at the printing position, the platen 5 thus forming a common impression surface for the types. Normally the platen is held in lowered position to permit the insertion of the work by means of the spring 28 which is attached at its other end to the arm 32 10 of the lever.

A means is preferably provided for precisely centering the types in printing position and for locking the carrier during the printing operation. One form of mechanism suitable for this purpose is shown as comprising a cam 37 on the shaft 29 adapted to engage and raise an extension 38 of an arm 39 pivotally supported on a spindle 40 and provided at its forward end with a beveled point 41 adapted to engage in beveled notches in a wheel 42 (Fig. 3), fixed on the shaft 14. One of these notches is provided to correspond with each of the type forms, and it will be understood that at the beginning 25 of the rotation of shaft 29, cam 37 rocks the arm 39, and the point 41 entering the notch corresponding to the selected type form accurately centers the latter in position and locks the carrier until the shaft 29 30 is returned to its initial position, when the point 41 is raised and disengaged from the wheel by means of a spring 50 attached to an extension of arm 39.

The feeding mechanism comprises, preferably, as a means for advancing the work, a pair of feed wheels 43 fixed on a shaft 44 which is journaled at its rear end in the rear wall of the casing, and at its forward end in a lug 45 depending from the bed 13. These 40 wheels extend through openings in the bed to position to engage the work, and the latter is pressed against the wheels by means of a pair of rollers 46 journaled in a yoke 47 which is pivotally supported on a spindle 48 45 and has a rearwardly extending arm 49 to which is fixed the spring 50. This spring presses the rolls 46 against the work, but the rolls may be raised to permit the insertion and removal of the paper by means of a rod 51 pivotally connected to the arm 49 and extending upwardly through the cover of the casing and provided at its upper end with a finger piece 52. The construction thus far described is similar to that disclosed in the 55 copending application of Todd and Tiefel, Serial No. 24,810, April 29th, 1915, for an improvement in check writers.

The shaft 44 has fixed near its rear end a ratchet wheel 53 with which is adapted to 60 engage a pawl 54 pivotally carried by a member 55 rotatably supported on the shaft 44. The pawl is provided with a projecting pin 56, and a spring 57 engaging this pin presses the pawl toward the ratchet wheel 65 53. The member 55 is adapted to be par-

tially rotated about the shaft 44 by means of a pin 58 fixed on said member (Fig. 5) and engaging in a slot 59 in a yoke 60 which has forklike arms embracing shaft 44 so as to guide it for vertical movement. The yoke 70 60 has an upwardly extending shank 61 and is normally held in its lowermost position with the pawl 54 at the extremity of its movement toward the right, as seen in Fig. 5, by means of a spring 62 attached to the 75 shank 61. Yoke 60 is adapted to be raised, however, to swing the pawl toward the left to engage and turn the ratchet wheel, through the operation of a bell crank lever 63 journaled on a spindle 64 and having an 80 arm 65 pivotally connected to the upper end of the shank 61. The lever has an upwardly extending arm 66 adapted to be engaged by a cam 67 on the shaft 29, so positioned that at the beginning of each revolution of the 85 shaft the cam rocks the lever 63 against the tension of the spring 62 and thereby first swings the pawl toward the left, as seen in Fig. 5, to turn the ratchet wheel, and then to return the pawl, idly, to its starting 90 position.

As the types on the carrier vary considerably in length, means must be provided for correspondingly varying the uniform feeding movement of the parts so far described. 95 This means comprises, preferably, a tripping device in the form of a sector plate 68 rotatably carried by the shaft 44. This plate has a circumferential edge concentric with the shaft 44, and at such a radial distance from the shaft as to engage and raise the pin 56, thereby lifting the pawl out of contact with the ratchet wheel. The parts are so arranged that when the pawl is in starting position it is adjacent the end 69 of 100 the edge of the plate 68, and it will be seen that the active stroke of the pawl carries it past the end 69 of the plate and that the pawl drops into engagement with the ratchet as it passes this point 69, so that the pawl 105 may be made to engage the ratchet earlier or later during the first part of its stroke by the rotary adjustment of the plate 68. The means for adjusting this plate comprises, preferably, a pin 70 fixed thereon and engaging in a slot 71 of a yoke 72 which has depending forklike arms embracing the shaft 44 to guide the yoke for vertical movement. The yoke is provided with an upwardly extending shank 73 to which is pivotally attached one arm 74 of a lever 75 pivoted on the spindle 27, and having a forwardly extending arm 76 provided with a roller for contact with the outline of a cam 77 fixed on the shaft 14. The cam is so designed that when a given type is in printing position the point on the outline of the cam which is in contact with the roller is at a radial distance from the center of shaft 14 corresponding to the length of this type 110 115 120 125 130

form, and the shorter the type form the longer the radius of the corresponding point on the cam outline, and vice versa. The roller is preferably held in engagement with the cam by the tension of spring 62 which is attached at its other end to the yoke 72. Thus, for a long type in printing position, a low portion of the cam 77 is in contact with the follower so that the yoke 72 is raised and the plate 68 swung in a clock-wise direction, as seen in Fig. 6, so that the pawl is allowed to drop, quickly, into engagement with the ratchet wheel and to impart a relatively large movement to the feed wheels. Correspondingly, when a short type is brought to printing position, plate 68 is rotated in a counter clock-wise direction, as illustrated in Fig. 7, so that the pawl engages the ratchet only toward the end of its movement and feeds the paper a corresponding short distance. It will be noticed that the active stroke of the pawl is produced by the application of a positive force, and it is therefore moved at a more uniform speed than would be obtained from the reactive force of a spring.

To further control the feeding movement imparted to the work and insure its accuracy, a device is provided for preventing any excessive movement due to an overthrow of the ratchet wheel. This device comprises a stud 78 fixed to the casing and carrying an adjustable stop member, or screw, 79, in position to engage the pawl 54 at the extremity of its active stroke, as illustrated in dotted lines in Fig. 6, so as to hold it in locking engagement with the ratchet wheel, so that the latter cannot overtravel as a result of its inertia. The ratchet wheel is prevented from any movement in a reverse direction by means of a ball 80 engaging one of the feed wheels 43 and carried in an inclined bore 81 in a frame 82, so that while the ball is rotated freely by the feed wheels in their forward movement, any reverse movement of the wheels tends to clamp the ball in its socket and lock the wheels against movement.

The operation of the machine needs but a brief description. The type carrier is adjusted, as already described, to bring the desired types, individually, in order, to printing position, and as each type is brought to printing position the tripping device, or plate 68, is rotatably adjusted to determine the extent of the feeding movement to correspond with the length of the respective type, and after each adjustment of the carrier the operating crank 30 is given a complete rotation, at the commencement of which the carrier is centered and locked in position. The feeding mechanism is then actuated to advance the work to bring a blank portion of the paper on the printing line to position beneath the selected type form, and

the platen is then raised into printing contact with the type. The rotation of the crank having been completed, the platen and feeding mechanism are returned to initial position and the type carrier is released for the next operation.

The protective quality of the inscription printed on a check writing machine depends largely upon the accurate spacing of the words, to prevent alteration by the substitution or insertion of other characters. The present invention, therefore, affords an important advantage in providing an accurate and reliable feeding mechanism. The rotary operating crank is moved at a substantially uniform speed by the operator, and the feeding mechanism being actuated by a positive connection with the crank, it will be apparent that a uniform feeding movement will be secured, an additional means to this end being provided in the device for preventing the overthrow of the work advancing means due to the inertia of the parts.

Having thus described my invention, what I claim as new, and desire to secure by Letters Patent is:—

1. In a machine of the class described, the combination with a movable type carrier provided with type lines of different lengths movable selectively to a common printing position, of a platen, means for effecting a relative printing movement between the type carrier and platen, a cam rigid with the type carrier, having its periphery graduated to correspond to the lengths of the various type lines, means for feeding the work, devices actuated by the cam for determining the extent of the feed, and a stationary stop co-operating with the feeding means to positively limit the extent of feed.

2. In a machine of the class described, the combination with a rotatable type carrier, having type lines of different lengths upon its periphery, of a cam moving with the type carrier and having its periphery graduated to correspond to the lengths of the various type lines, means for feeding the work, devices moved from one position to another by movement of the cam for determining the extent of the work feed, and a stop co-operating with the feeding means to positively limit the extent of the feed.

3. In a machine of the class described, the combination with a cylindrical type carrier having type for printing words of various lengths, rolls constructed to be rotated to feed the work, a cam having its periphery graduated to correspond to the lengths of the various words, means for moving said cam, a member constantly in engagement with and actuated by movement of said cam, means controlled by said member for actuating the feed rolls various distances corresponding to the lengths of the types, and a

stationary stud for positively limiting movement of the actuating means.

4. In a machine of the class described, the combination with a rotatable type carrier, having on its periphery type lines of different lengths, of a cam connected for rotation in unison with the type carrier, feeding rolls for advancing the work, ratchet and pawl mechanism for actuating the feeding rolls in one direction, means for giving the pawl an invariable excursion, means set

by movement of the aforesaid cam for determining the point of initial engagement of the pawl with the ratchet, and a stop engaged by the pawl at the end of its invariable excursion, said stop and pawl co-operating to prevent over rotation of the feeding rolls. 15
